UNITED STATES PATENT OFFICE.

THOMAS CLARKE, OF TRURO, NOVA SCOTIA, CANADA.

PERMANENT FIRE-ESCAPE.

SPECIFICATION forming part of Letters Patent No. 291,688, dated January 8, 1884.

Application filed April 16, 1883. (No model.)

To all whom it may concern:

Be it known that I, THOMAS CLARKE, of Truro, in the county of Colchester and Province of Nova Scotia, Canada, have invented 5 certain new and useful Improvements in Permanent Fire-Escapes; and I do hereby declare that the following is a full, clear, and exact description of the invention, which will enable others skilled in the art to which it appertains 10 to make and use the same, reference being had to the accompanying drawings, which form a part of this specification, and in which—

Figure 1 is a sectional view of part of a building provided with my improved fire-escape. Fig. 2 is a front or face view of one of the windows of the building, showing the escape in position fronting the same. Fig. 3 is a top or plan view of the cage which forms part of my improved fire-escape. Fig. 4 is a 20 sectional detail view of the spring-windlass for operating the cage; and Figs. 5 and 6 are detail views of certain parts of the same, which will be hereinafter more fully explained in describing the construction and operation 25 of the windlass.

Similar letters of reference indicate corresponding parts in all the figures.

My invention has relation to permanent fire-escapes, or that class of escapes which are attached permanently to and form part of a 30 building; and it consists in the construction and arrangement of parts of the same, as hereinafter more fully described, and particularly pointed out in the claims.

In the accompanying two sheets of drawings, A denotes the front wall of a building provided with one of my improved escapes.

B denotes one of the windows in the building, above which, under the roof or eaves, are 40 suitably attached beams or anchors C, the free ends of which project a suitable distance out over the front wall, to permit the traveling cage or car, which constitutes a part of my invention, to swing free of the window-sills or 45 other projecting parts of the building. The outer ends of the supports or anchors C are connected with the ground by stays D, which may be made of iron or steel rods, or by twisted wire rope or chains, as may be desired.

In the drawings I have shown the stays D

D bolted to hangers or stirrups a, which in turn are firmly bolted to the outer ends of the beams or hangers C. The lower ends of the stays D should be anchored firmly in the 55 ground, or in some suitable support near the ground, in any desired manner, and said ground-anchors should be provided with means for tightening the stays or taking up slack whenever required.

Hung in the outer end of each of the anchors C is a sheave or snatch-block, E, over which the hoisting-ropes F are passed, there being one hoisting-rope for each of the sheaves, as clearly shown in Fig. 2.

To the free ends of the hoisting-ropes F is hung a car or cage, G, which may be made of thin steel or iron rods, or of wire-netting, so as to make it strong and durable with a minimum weight. The top part, g, of this cage 70 may be made of chains, so that it will fold down or collapse when the cage is not in use, and thus reduce the size of the same, so that it will stow itself out of the way underneath the projecting eaves, or at any suitable receptacle in the top part of the building, and be always ready for use whenever wanted, without any preparation. The lower part of the cage is provided with a hinged door, H, which, when the cage is in position opposite a window 80 in the building from which escape is to be made, may be swung down with its free end resting upon the window-sill, so as to form a bridge or platform connecting the window with the cage, thereby making accidents impossible 85 if a person should make a false step in trying to reach the cage from the window. An outer door, H', is also provided for exit on reaching the ground. As these doors shut upwardly, as shown in dotted lines in Fig. 1, they will in 90 no manner interfere with the descent of the cage, and will swing open by their own gravity whenever the cage is stopped in front of a window during its descent.

I prefer to construct the floor or bottom of the cage of thin metallic slats, as shown at b in Fig. 3, and the bottom brace, as well as one or more of the top bars, should be provided with extensions I, the outer ends of which form loops or eyes i, through which the stays D D 100 are passed, as shown in Fig. 3 of the drawings. By means of these fixed stays or ways

the cage will have a true upward and downward motion when in use, whether the stays (which must of course be parallel to each other) are parallel to the wall of the building, or 5 whether they are placed in a slanting or inclined position relative thereto.

The hoisting-ropes F pass through a suitable aperture in the wall into the interior of the building, and are connected to the drum K of the windlass L. In the present illustration of 10 my invention I have shown this windlass journaled in hangers M, which are fastened to beams N in the top part of the building; but it is obvious that the windlass may be arranged 15 in any other desired manner or at any other suitable location, as may be found convenient or expedient, so that it will occupy a proper position for working the hoisting-ropes and the cage or cradle supported at the free 20 ends of the same, and be always ready for use without any preparation.

In Fig. 4 of the drawings I have shown a sectional view of the windlass, from which it will be seen that the same consists of a hollow 25 drum or cylinder, K, which is journaled at opposite ends in the hangers M.

P is the shaft of the drum, which is inserted centrally and longitudinally through the same, with its inner end, Q, inserted into a recess, r, 30 in the head R of the drum or cylinder. The central shaft, P, is encircled by one or more coiled or spiral springs, (shown at S,) the ends of which springs are fastened on one side in one of the heads R, while the other ends are 35 fastened in the central shaft, P.

To the projecting end of the shaft P is attached a crank, S', which has a clutch, T, adapted to engage a corresponding clutch, U, which is fixed upon the adjacent head R of the 40 cylinder in such a manner that when the clutch T is pushed against the head of the cylinder the clutches T and U will mesh with or engage one another, thereby turning or rotating the drum, while the clutch U will become disengaged from the crank-clutch T, when the shaft is rotated in the opposite direction. A 45 flat bolt, V, slides in ways R' upon the cylinder-head, and in a transverse recess in the half-clutch U, and is provided upon its inner 50 end with a rectangular slot or notch, v, open at the end, which fits over the square portion p of the shaft P when pushed in, and is provided at its outer end with a knob, v', or similar means for drawing the bolt out or pushing it in. In this manner, when the flat bolt is 55 pushed in and the two half-clutches engage, the windlass will be rotated with the shaft and crank, operating as an ordinary windlass, while when the bolt is withdrawn and the 60 clutches disengaged the descending cage will wind the spring, which will again rotate the cylinder, winding the rope and raising the cage, when the weight of the persons descending in the cage is removed, thus operating the 65 escape automatically without the need of a person to operate the windlass.

The drum of the cylinder, around which the hoisting-ropes F are wound, is provided with an ordinary lever-brake, W, which is actuated by a cord or thin wire rope, X, the free end 70 of which passes over a small sheave or pulley, Y, which may be conveniently attached to the inner side of one of the anchor-beams C. The free end of the brake-cord is attached to a roller, Z, journaled in the frame of the cage, 75 and being of the same construction as a watch or clock drum, the brake-cord winding the spring when the cage is descending, which spring will then serve to wind the cord upon the drum or roller, when the cage ascends again. 80 In this manner provision is made for keeping the brake-cord taut during the ascent or descent of the car or cage G. To the bottom of the car is attached a wire rope or chain, c, which reaches to the ground below, so that the car 85 may be lowered by a person standing on the ground or at any one of the windows by pulling said cord c.

One of the chief drawbacks to the efficiency of permanent fire-escapes in the event of a 90 fire arises from the fact that their precise location in the building is not readily ascertained during the confusion incident to a fire, especially in a large hotel full of transient guests, many of whom may have arrived on 95 late trains, and have had no opportunity for ascertaining the means of escape in the event of a fire. I therefore place outside of the window in each story, which is passed by the cage on its ascent or descent, an automatic device which will operate an alarm every time the cage or car goes up or down. A device of this kind is shown in Fig. 1 of the drawings, from which it will be seen that it consists simply of a lever, h, having an elastic knob, 105 i, at its outer end, and hinged at its inner end, j, to a suitable support affixed in the wall of the building, either below or above the window, or on one side thereof. Lever h is held in its horizontal or extended position by means 110 of two curved springs, k k, which are fixed in the wall, and bear with their curved outer ends against the lever, as clearly shown in the drawings. Bell-cords (shown at l) connect lever h with a bell or gong placed in the hall of 115 the building, there being one of these for each story, and as the car or cage travels up or down past the different stories, an alarm is struck each time it is opposite to one of the windows of egress, so that the guests can have 120 no difficulty in finding the means of exit, nor can they fail to know the precise moment when the car is there ready to carry them out of the burning building. It is obvious, however, 125 that this device may be modified in its construction without materially deviating from the spirit of my invention.

Having thus described my invention, I claim and desire to secure by Letters Patent of the United States—

1. The combination, with a building, of parallel ways or stays attached permanently there-

to, a cage or car traveling upon said ways or stays, and provided with ropes for hoisting it up or down, a spring-actuated windlass adapted to hoist the car by the tension of the spring when wound, a brake mechanism actuated by a cord, the lower end of which is connected to a spring-roller inside of or attached to the outside of the traveling car or cage, and a rope or chain attached to the bottom of the same, by means of which it may be drawn down to the bottom of the building, the whole constructed and arranged to operate substantially in the manner and for the purpose shown and set forth.

15 2. The combination, with a building, of parallel ways or stays attached permanently thereto, a cage or car traveling upon said ways or stays, and provided with ropes for hoisting it up or down, a spring-actuated windlass adapted to hoist the car by the tension of the spring when wound, a brake mechanism actuated by a cord the lower end of which is connected to a spring-roller removably attached to the traveling car or cage, a rope or chain attached to the bottom of the same, by means of which it may be drawn down to the bottom of the

building, and an alarm adapted to be operated automatically by the car as it travels up or down, the whole constructed and arranged to operate substantially in the manner and for the purpose shown and set forth. 30

3. The combination, in a permanent fire-escape, of a cage or car adapted to travel up or down in front of the windows of a building, with alarm devices located at the said windows, and having projecting arms engaging with the passing cage, operating the alarm, as and for the purpose shown and set forth. 35

4. The car or cage G, provided with a collapsible top, g, eyes i, for guiding it upon the ways, and doors H, adapted to open in a vertical plane, so as to form a platform connecting the windows of the building with the car when the apparatus is in use, substantially as and for the purpose shown and set forth. 40

In testimony that I claim the foregoing as my own I have hereunto affixed my signature in presence of two witnesses.

THOMAS CLARKE.
